US0D1110011S

(12) United States Design Patent (10) Patent No.: US D1,110,011 S
(45) Date of Patent: * Jan. 27, 2026

(54) SHOE

(71) Applicant: NIKE, Inc., Beaverton, OR (US)
(72) Inventor: Lauren Sebastian, Portland, OR (US)
(73) Assignee: NIKE, Inc., Beaverton, OR (US)
() Term: 15 Years

(21) Appl. No.: 29/962,377

(22) Filed: Sep. 11, 2024
(51) LOC (15) Cl. 02-04
(52) U.S. Cl. USPC D2/972

(58) Field of Classification Search

USPC ..... D2/296, 902, 903, 905–909, 916, 919, D2/923, 947, 951–960, 977, 900, 944, D2/969, 925, 929, 943, 946, 971–975; 36/3 B, 22 R, 24.5, 25 R, 28, 32 R, 34 R, 36/59 C, 67 A, 103, 114
CPC A43B 1/00; A43B 1/10; A43B 1/12; A43B 1/14; A43B 1/02; A43B 1/023; A43B 1/025; A43B 1/028; A43B 1/05; A43B 5/00; A43B 5/001; A43B 5/002; A43B 5/003; A43B 5/007; A43B 5/008; A43B 5/02; A43B 5/06; A43B 5/08; A43B 5/10; A43B 5/12; A43B 5/14; A43B 13/00; A43B 13/02; A43B 13/023; A43B 13/026; A43B 13/04; A43B 13/08; A43B 13/10; A43B 13/12; A43B 13/14; A43B 13/141; A43B 13/143; A43B 13/16; A43B 13/18; A43B 13/181; A43B 13/187; A43B 13/189; A43B 13/20; A43B 13/22; A43B 13/223; A43B 13/28; A43B 13/30; A43B 13/32; A43B 13/34; A43B 13/36; A43B 23/00; A43B 23/02; A43B 23/021; A43B 23/0215; A43B 23/022; A43B 23/0235; A43B 23/0245; A43B 23/26; A43B 23/30

CLAIM

The ornamental design for a shoe as shown and described.

DESCRIPTION

FIG. 1 is a front perspective view of a shoe showing my new design;

FIG. 2 is a side view thereof;

FIG. 3 is an opposite side view thereof; and,

FIG. 4 is an opposite side front perspective view thereof. The broken line immediately adjacent to the photographic area defines a peripheral bound of the claimed design and forms no part thereof. The broken lines depicting the remainder of the shoe form no part of the claimed design.

1 Claim, 4 Drawing Sheets
